DISPENSING AND DISPLAY CONTAINER

John W. Hoover, Los Altos, Calif., assignor to Fibre-board Paper Products Corporation, San Francisco, Calif., a corporation of Delaware

Application July 13, 1956, Serial No. 597,757

5 Claims. (Cl. 211—50)

This invention relates to containers, and more particularly to a dispensing and display container for the merchandising of flat rectangular shaped objects such as floor covering tile.

Summarizing the invention, the dispensing and display container comprises an upright framework having walls through which the objects are visible and which form a bin for a stack of such objects supported in columnar overlying relationship. The horizontal cross-sectional shape of the bin is of substantially the same size as the objects. Desirably, the framework and bin are formed of metal rods secured together and which provide spaces therebetween through which the tile are visible. To enhance the effectiveness of the display and to support the tile above the floor upon which the framework is supported, and also to reinforce the structure, a support platform is provided for the bottom of the stack, which is elevated above the bottom of the framework.

Each wall of one pair of opposite walls of the framework is slotted substantially the entire length between the stack support platform and the top of the framework to facilitate manual removal of the tile. At the same time, these slots provide resiliency to enable spreading apart of the other pair of walls of the framework to facilitate insertion of the tile into the bin. Another desirable feature is the incorporation of a display frame mounted on the framework and which is swingable from a position below the top of the framework to a position above the top and vice versa, for displaying printed advertising matter.

From the preceding, it is seen that the invention has as its objects, among others, the provision of an improved dispensing and display container which is of such construction as to enable ready visibility of the objects contained therein, which will facilitate both manual insertion and removal of the objects, and which is of simple and economical construction. Other objects of the invention will become apparent from perusal of the following more detailed description thereof.

Referring to the drawings:

Fig. 1 is an isometric view of the container of this invention, illustrating in phantom lines a columnar stack of flat rectangularly shaped floor covering tile supported thereon.

Fig. 2 is a vertical longitudinal cross-sectional view taken in a plane indicated by the line 2—2 in Fig. 1, with a central portion of the framework broken away to shorten the view.

Fig. 3 is a rear elevational view adjacent the top of the framework illustrating the same with the display frame in down position.

Fig. 4 is a view similar to Fig. 3 but with the advertising frame illustrated in raised display position.

The container is formed desirably entirely of rod or wire members, preferably of metal, and comprises a rectangular bottom support 2 adapted to rest on a supporting structure such as a floor or display table. Suitably secured to bottom support 2 by spot welding or

2

brazing or by any other means are a plurality of upright rod members 3 spaced apart as illustrated in Fig. 1. Rods are not provided at the corners; so that the container is unobstructed and open at all four corners. The rods adjacent each corner form part of an integral rod structure bent at its upper end to provide a right angularly shaped top portion 4 connecting such corner rods to reinforce the structure.

Adjacent to and in elevated relationship with respect to bottom support platform 2 is a stack support 6 also formed of rod members suitably secured by spot welding or brazing to the rods 3; the stack support platform 6 being of substantially the same rectangular shape as the shape of tile 7. Each corner 8 of stack support platform 6 projects between the rods 3 adjacent each open corner of the container, as do the unconcealed corners of the tile, thus enhancing the display effect. By spacing stack support platform 6 above bottom support 2, not only does this enhance the display effect but it also serves to reinforce the structure by providing two spaced apart locations of attachment of rods 3.

It will be noted that stack support platform 6 is spaced apart from bottom support 2 a little less than $\frac{1}{4}$ the height of the container, thus forming a tile receiving bin 9 spaced above the bottom of the structure. The horizontal cross sectional shape of such bin is of substantially the same size as the tile to effect a neat display.

Each of one pair of opposite walls of the bin formed by the rods 3 at the left and right sides thereof as appearing in Fig. 1, is slotted at 10 the entire length between stack support platform 6 and the top of the bin. These slots 10 result from the spacing apart of two rods 3 included in each of such side walls. In addition, the rods 3 included in the other pair of opposite walls forming the front and rear walls of the bin are secured together by horizontal reinforcing rods 11 and 11' on the front and rear walls, respectively, and which are located below the top of the bin. Slots 10 facilitate manual removal of the tile because one desiring to remove the tile can readily insert his hands into the slots and lift out the tile without interference. Also, such slots provide resiliency so that the front and rear walls of the bin can be spread apart to facilitate insertion of the tile into the bin upon stacking thereof. Reinforcing rods 11 and 11' also provide handles for lifting the bin with tile therein when this is desired.

A display frame is desirably mounted on the container so that advertising matter for the product, such as price or style, can be placed thereon for ready visibility to the customer. Such advertising frame comprises a metal wire bent to form a rectangular frame portion 12, and legs 13 provided with eye portions 14 at their lower ends swingably mounted on the rear reinforcing member 11'. A flat plate 16 for carrying the advertising matter is mounted on frame portion 12.

Rear reinforcing member 11' is formed with hooks 17 at its ends to engage the rear sides of legs 13 in the elevated position of the display frame and hold it in such position. The display frame can be readily raised from its position below the top of bin 9 to a display position above the same as shown in Fig. 4 merely by pinching legs 13 together and pivoting the frame upwardly. By engaging legs 13 in front of the hooks 17, such frame will be held in elevated position. Lowering of the display frame can be quickly effected in a reverse manner.

The described container not only provides an effective display and dispensing container, but also it can be used as a package for shipment of the objects when so desired.

I claim:

1. A dispensing and display container for a stack of rectangularly shaped flat floor covering tile or the like comprising an upright framework of rods providing spaces

therebetween through which tile are visible, said framework forming a bin for said tile stack of rectangular horizontal cross-sectional shape of the same size as said tile, the bin being open at all four corners thereof, a support platform for supporting the bottom of said stack attached to said rods and elevated above the bottom of said framework, each wall of one pair of opposite walls of the bin including two upright rods spaced apart to provide a slot extending substantially the entire length between said stack support platform and the top of said framework to facilitate manual removal of tile from said bin and providing resiliency to enable spreading apart of the other pair of walls of the bin to facilitate insertion of tile into said bin, each wall of said other pair of walls including two upright rods and a transverse reinforcing rod connecting the same, the upright rods of the respective walls of said framework which are adjacent and define each corner of the bin being connected together at their tops.

2. The container of claim 1 in which a display frame is mounted on one of said reinforcing rods for swinging movement from a position below to a position above the top of said framework and vice versa.

3. An open framework dispensing and display container for a stack of polygonally shaped objects comprising pairs of opposite walls extending upright from a polygonal bottom support, each of said walls including at least two upright elongated rods connected at their bottom ends to said support, each of the opposite walls of a pair of said walls having a transverse reinforcing rod extending between the upright rods thereof, one of said transverse rods providing mounting means for securing a swingable display frame to said container, a display frame positioned on said one rod, said display frame being movable between a lower position below the top of said framework and an elevated position above the top of said framework, said one transverse rod including means for holding said display frame in said elevated position, and a flat polygonal stack support platform extending between said pairs of walls and connected thereto, said platform

being spaced above said bottom support and extending substantially parallel thereto to space said objects from the surface upon which said container rests.

4. An open framework dispensing and display container for a stack of rectangular flat floor covering tile or the like comprising pairs of opposite walls extending upright from a flat bottom support for said container, each wall including at least two upright elongated rods connected at their bottom ends to said support, a flat stack support platform connected between said walls at a location spaced above said bottom support, said platform and said walls forming a tile receiving bin therebetween having a rectangular horizontal cross-section substantially the same size as said tile, each of the opposite walls of a pair of said walls being slotted substantially the entire length between said platform and the top of said framework to facilitate insertion and removal of said tile relative to said bin, each of the opposite walls of the other pair of said walls including a transverse reinforcing rod extending between the upright rods thereof, one of said transverse reinforcing rods providing mounting means for securing a display frame to said container, and a display frame swingably positioned on said one rod and movable between a lower position below the top of said framework and an elevated position above the top of said framework.

5. The container of claim 4 wherein said one transverse reinforcing rod includes hook shaped extensions engageable with said display frame for holding the same in the elevated position.
